UNITED STATES PATENT OFFICE

133,415

DESIGN FOR A COMBINED BOTTLE AND CLOSURE

Paul M. E. Mayer, New York, N. Y.

Application February 11, 1942, Serial No. 105,766

Term of patent 7 years

To all whom it may concern:

Be it known that I, Paul M. E. Mayer, a citizen of no country, residing at 215 East 22nd Street, city of New York, in the county and State of New York, have invented a new, original, and ornamental Design for Combined Bottle and Closure, of which the following is a specification, reference being had to the accompanying drawing, forming part thereof, wherein—

Fig. 1 is a top plan view of the combined bottle and closure showing my new design;

Fig. 2 is a perspective view thereof.

I claim:

The ornamental design for a combined bottle and closure, as shown.

PAUL M. E. MAYER.
